INVENTOR,

A. H. Gay.

Att'y.

UNITED STATES PATENT OFFICE.

ALBERT HARDY GAY, OF LONDON, ENGLAND.

SOUND BOX FOR TALKING MACHINES.

1,418,249.

Specification of Letters Patent. Patented May 30, 1922.

Application filed April 20, 1921. Serial No. 462,817.

To all whom it may concern:

Be it known that I, ALBERT HARDY GAY, a subject of the King of Great Britain and Ireland, residing at London, England, have 5 invented certain new and useful Improvements in Sound Boxes for Talking Machines, of which the following is a specification.

This invention relates to sound boxes for talking machines and has for its object to 10 increase the volume of the reproduction, and to obtain a reproduction more closely approaching the original, as regards tone and articulation.

The invention has also for its object to 15 reduce to the minimum the hissing, and other undesirable surface noises incidental to talking machines and the like sound reproducing instruments.

The invention consists in the features of 20 construction combination and arrangement of parts, hereinafter more fully described with reference to the accompanying drawings and claimed in the appended claim.

In the drawings wherein like reference numerals are employed to indicate corresponding parts in the various figures:

Figure 1 is a sectional side elevation of the complete sound box.

Figure 2 a front elevation corresponding 30 to Figure 1, but with the cap 22 removed.

Figure 3 is a sectional side elevation corresponding to Figure 1 but turned through an angle of 90°.

Figure 4 is a front elevation looking in 35 the direction of the arrow in Figure 3.

Figure 5 is a sectional side elevation showing modified connecting means for the tone arm, and

Figure 6 is an enlarged detail view showing 40 more clearly the means for insulating the stylus bar and bracket for the fulcrum pin, from said fulcrum pin.

Referring to the drawings, an open ended circular casing 1, of metal such as brass or 45 aluminium, forming the sound box proper, and somewhat deeper than the usual sound box, is reduced circumferentially at one end hereinafter referred to as the back end, to form a shoulder 2, and has an inwardly projecting flange 3 extending from such reduced end.

Two rings 4, 4, of hollow formation and 50 constructed of rubber are fitted in the casing 1, and are adapted to receive between them the diaphragm 5, at its edge.

A cover 6 is screwed on the other end of

the casing 1, hereinafter referred to as the front end, and serves to retain the rings 4 in position between it and the inwardly projecting flange 3, the diaphragm 5 being 60 thereby clamped between the rings 4. 4.

This front cover 6 has a central outwardly extending boss 7, formed with a bore 8 of tapered or flared form, the wider end opening directly into the casing 1, opposite to the 65 diaphragm 5.

It is preferred to form this bore, with curved walls in cross section as shown so as to produce as it were a trumpet mouth.

A ring of fibre 9 is screwed on the boss 7, 70 at its outer end, such ring 9 being insulated from the boss by a ring of rubber 10 which is interposed between the facing surfaces.

The fibre ring 9 is of somewhat less external diameter and of somewhat greater internal diameter than the corresponding diameters of the boss 7, and is secured on the boss 7, concentrically therewith.

An outer metal ring 11 preferably brass is slipped on to the fibre ring 9 so that its outer 80 surface is flush with the outer surface of the boss 7, and rubber ring 10, and an inner metal ring 12, preferably aluminium is fitted in the fibre ring 9, the bores of the rubber and inner rings 10 and 12 forming a continuation of the bore 8 of the boss 7 but with 85 parallel walls.

The various rings may be secured in position in any suitable manner for example by frictional engagement alone or by screws. 90

The casing 1 has secured on its circumference a bifurcated bracket 13 to receive the fulcrum pin 14 for the stylus bar 15, which is secured to the diaphragm 5 in the usual manner at one end and is bent and enlarged 95 somewhat at the other end, as shown at 16 which is to be pivoted in the bracket 13.

In order to prevent direct metallic contact between the stylus bar 15 and its fulcrum pin 14 the apertures provided in the 100 bifurcated bracket 13 to receive the fulcrum pin 14, are fitted with fibre bushes 17 and the aperture in the stylus bar 15 through which the fulcrum pin 14 passes is similarly bushed, as indicated by the reference numeral 18 and more clearly shown in Figure 6.

In addition to this insulation, an inverted U-shaped piece of sheepskin 19 of a thickness of about $\frac{1}{8}$ inch is fitted between the bifurcations of the bracket 13 so that the limbs 110 of the inverted U are disposed between each bifurcation and the stylus bar 15, and the

fulcrum pin 14, is passed through the limbs of the inverted U-shaped insulator 19.

The stylus bar 15 is provided at its free end with a socket 20 to receive the needle, such socket 20 having a set screw 21 for clamping the needle in position.

The circumferentially reduced end of the casing is adapted to receive a hollow cap 22 constructed of wood, the edge of the cap 22 bearing against the shoulder 2 formed on the casing 1 by reducing the diameter thereof as hereinbefore described.

The cap 22 is reduced in diameter internally for a short distance inwardly to form a rabbeted joint 23, and is provided with an aperture 24 in its wall, to allow the stylus bar 15 to pass therethrough.

In order to enable the sound box to be connected to the tone arm, which is of the well known form and therefore does not require to be described or shown, two studs 25 are secured in diametrically opposite positions, on the ring 11, for engagement in the usual slots in the tone arm.

These studs 25 as shown more clearly in Figure 3 consist of short lengths of tube surrounding screws 26 which pass through the ring 11 into the fibre ring 9.

Alternatively and as illustrated by Figure 5 the fibre ring 9 may have formed therein in diametrically opposed positions two cavities 27 in which are arranged springs 28 adapted to bear on balls 29 fitted in sockets 30 formed in the ring 11, the sockets being such as to permit the balls to be projected outwardly by the springs beyond the periphery of the ring 11 but to prevent them passing entirely through the ring 11.

The balls 29 are adapted in the connected position of the sound box and tone arm to engage in sockets in the form of apertures 31 in the wall of a circular casing 32 provided at the end of a tone arm 33, which is here shown broken away as the only unusual fea-

ture is the addition of the casing 32. This casing 32 is provided internally with a circumferential groove 34 which connects the apertures 31.

By means of this connection the sound box can be rotated or swung round relatively to the casing 32, to facilitate insertion of the usual playing needle, in its socket 20, the balls 29 being pressed inwardly against the action of their springs 28, and running in the groove 34. When the needle has been inserted in its socket 20, the sound box is rotated in the opposite direction, the balls 29 again running in the groove 34 until they reach the apertures 31, whereupon they snap into the apertures 31 under the action of their springs 28, thereby ensuring the return of the sound box to the correct playing position.

Alternatively the balls 29 could be arranged in the casing 32, and the groove 34 and sockets 30 in the neck of the sound box.

With such a sound box it is found that a sound reproduction can be obtained, which is of increased volume, and is practically free from the undesirable hissing and other surface noises incidental to talking machines.

I claim:

A sound box for talking machines having a bifurcated stylus bar bracket, a fulcrum pin mounted in the respective arms of the bracket, a stylus bar mounted on the pin between the arms of the bracket, a strip mounted on the pin on opposite sides of the stylus bar mounting and serving to maintain said stylus bar mounting in a predetermined position longitudinally of the pin and spaced from the arms of the bracket, and an insulating section arranged between the pin and the stylus bar mounting.

In testimony whereof I have signed my name to this specification.

ALBERT HARDY GAY.
